UNITED STATES PATENT OFFICE.

ARTHUR HALE, OF ROWLANDSVILLE, MARYLAND.

STREET-CROSSING.

1,173,505.

Specification of Letters Patent. Patented Feb. 29, 1916.

Application filed May 24, 1915. Serial No. 30,152.

To all whom it may concern:

Be it known that I, ARTHUR HALE, a citizen of the United States, residing at Rowlandsburg, in the county of Cecil and State 5 of Maryland, have invented certain new and useful Improvements in Street-Crossings; and I do hereby declare the following to be a full, clear, and exact description of the invention, such as will enable others skilled 10 in the art to which it appertains to make and use the same.

This invention relates to street crossings and has for its object to provide a construction suitable for congested crossings which 15 will render it unnecessary for traffic going in either direction on one street to ever cross at grade the traffic going in either direction on the other street; or even to cross its own street at grade when it wishes 20 to reverse its direction of travel.

With this and other objects in view the invention consists in the novel constructions hereinafter more fully disclosed and particularly pointed out in the claims.

25 Referring to the accompanying drawings forming a part of this specification in which like numerals designate like parts in all the views: Figure 1 is a plan view of a street crossing made in accordance with my invention; Fig. 2 is a plan view of a slightly modified form of the invention; Fig. 3 is a plan view of a still further modified form of the invention; Fig. 4 is a sectional view taken on line 4—4 of Fig. 1; and Fig. 5 is 30 a sectional view taken on the line 5—5 of Fig. 1.

Referring more particularly to the preferred form of the invention illustrated in Fig. 1; 1 indicates a thorough-fare or street, 40 crossing a second thorough-fare or street 2, by means of a bridge or viaduct 3, provided with the raised grades 4 and 5, on each side of the street 2, and the level space 6 over said street 2. The street 2, is, further provided with depressions 7 and 8 joining the ends 10 of its level member on each side of the bridge 3, and with the level space 9 under said bridge (see Fig. 4). Between the ends 10 of the level members of the street 45 2, and the ends 13 of the level members of

the street 1, I provide the four level passage ways 14, 15, 16 and 17 as shown.

The traffic on one side of the street 1 I have designated by the arrows 25, while that on the other side of said street 1, I 55 have designated by the arrows 26. In the same way the opposing traffic on the street 2 I have designated by the arrows 27 and 28. It will thus be seen that the traffic 25 as it approaches the grade 4 will encounter an up 60 grade 29 on street 1, and will pass over a down grade 30 after reaching grade 5 on said street. In the same way traffic 27 on street 2 will encounter down grade 31 after leaving level 10, and will ascend up grade 65 32 after passing from under bridge 3. In the same way traffic 26 on street 1 first encounters up grade 33, and then down grade 34, while traffic 28 on street 2 first encounters down grade 35 and then up 70 grade 36. Between about the middle portions of the down grades 34 and 31 I provide the spiral or helical passage, or way 18, I provide a second helical way 20 between the up grade 29 and the up grade 32, a third 75 helical way 22 between the down grade 30 and the down grade 35, and a fourth helical way 23 between the up grades 33 and 36.

39, 40, 41 and 42 represent side walks, as do also 43, 44, 45, 46, 47, 48 and 49. 80

In order that the construction and operation of the invention so far as has now been disclosed may be clearly understood, it is said: Persons afoot wishing to go straight ahead in one direction on street 1, will follow the side walks 40, 46, 47, 48, 49 and 41 located on one side of said street, while those going in an opposite direction will follow side walks 42, 45, 44, 43 and 39 on the other side of said street. Should any of the first 85 named persons wish to turn into street 2, they will simply follow the side walk 40 associated with the level passage 15 and one side of street 2, or after passing down grade 30 and crossing level passage 16, they 90 may follow side walk 41 associated with said passage 16 and the other side of street 2. In the same way should any of the second named persons wish to turn into street 2 on either side thereof, they will follow side 95 100

walk 42, or cross level passage 14 and follow side walk 39. In the same way traffic 25 and 26 on street 1 merely keeps ahead as usual on their respective sides of said street unless it wishes to turn into street 2. Should traffic 25 wish to turn to the right, into street 2, it merely follows level passage 15, and joins traffic 27 in said street 2. Should it wish to go in the opposite direction or to 10 join traffic 28 in said street 2, then said traffic 25 will continue on to down grade 30, where it will turn on a tangent into the helical passage 22, and continuing on a down grade join traffic 28 in street 2 on a tangent. Finally should traffic 25 wish to reverse its direction and join traffic 26 on street 1, it will traverse helical passage 22 as just described, enter up grade 36 and traverse helical passage 23 on an up grade 20 and join traffic 26 on street 1.

It will thus be seen that in each of the four possible ways that traffic 25 may desire to go, it never crosses a street at grade, not even its own street. In the same way traffic 25 26, will traverse the level way 17 to join traffic 28 or it will traverse the down grade 34 and down grade spiral 18 to join the down grade traffic 27, or it will traverse the spiral or helical passage 18, the up grade 30 32, and the up grade helical passage 20, to joint the traffic 25 on its own street. Again traffics 27 and 28 on street 2 will keep ahead as usual unless they wish to turn into street 1. When it is desired to change the course 35 of the traffic 27, it may traverse the level way 14 to join traffic 26, it may traverse the up grade 32 and up grade helical way 20 to join the traffic 25, or it may traverse the helical ways 20 and 22 to join the traffic 28 in its own street. Traffic 28 in like manner will make use of the way 16 to join traffic 25, of the way 23 to join traffic 26, and of the ways 23 and 18 to join traffic 27 in its own street.

45 It will therefore now be clear that in no case is it necessary for any one of the four streams of traffic 25, 26, 27 and 28 to cross at grade another stream of traffic when going in any of the four directions each 50 stream might take, so that cross collisions are impossible.

It is an important feature of the invention that each of the helical passage ways 18, 20, 22 and 23 open on a tangent to their 55 associated lines of traffic, and it is another important feature of the invention that when one line of traffic is started up or down a grade, the particular helical passage which it takes is a continuation of its said 60 up or down grade so that the character of the passage way only changes in direction, thus further avoiding accidents.

Not only may lines of traffic thus go in any possible direction without danger of

collision, but the same is true of foot passengers as will be presently disclosed. That is to say in order to better accommodate foot passengers, I provide at or near the juncture of the ends 10 and 13 of the level portions of the street with their 65 grades, the sub-ways 60, 61, 62 and 63. I further provide on the side walk 39 entrances 64 and 65 to the sub-way 60, and on the side walk 40 the entrances 66 and 67 as shown. In connection with the sub- 75 way 61, I provide on the side walk 40, the entrances 68 and 69 and on the side walk 41 the entrances 70 and 71. In connection with the sub-way 62 I provide on the side walk 41 the entrances 72 and 73 and on the 80 side walk 42 the entrances 74 and 75. In connection with the sub-way 63 I provide on the side walk 42 the entrances 76 and 77, and on the side walk 39 I provide the entrances 78 and 79. In addition to the 85 above on the street 2, I may locate the railroad tracks 80 and 81 and may connect with the sub-way 61 a passage 83 leading to an 90 isle of safety 84 between the railroad tracks 80 and 81. A similar construction is provided at the sub-way 63 and the parts are similarly lettered.

Accordingly, it follows that should foot passengers going in the direction of the stream of traffic 25 wish to continue in said 95 direction, they may follow along the side walks 40, 46, 48, 49 and 41 as above stated, crossing the passages 15, 20, 22 and 16 which 100 passages will of course never be so congested as will the main street, but should they wish to avoid the crossing of any such 105 passages, then the said foot passengers will follow along the side walk 40 to the sub-way entrance 68 or 69, follow along the sub-way 61 and out the entrance 70 or 71, and continue their travel along the side walk 41 and in their original direction. Should such foot passengers on the other 110 hand wish to go in the direction of the traffic 27, they would merely follow the side walk 40. Should they wish to go in the direction of traffic 28, they would cross street 2 by means of the sub-way 61, 115 traverse the side walk 41, cross the street 1, by means of the said sub-way 62, and traverse the side walk 42 in the direction of traffic 28. Should the said foot passengers wish to reverse their direction on street 1, and walk in the direction of the stream of traffic 26, they would only have to traverse the sub-way 60, and emerge at the entrance 65. Should they wish to traverse 120 the side walk 39 in a direction opposite to the travel of traffic 27, they likewise cross street 1, by means of sub-way 60 and traverse side walk 39 in the direction desired. 125

As a matter of fact there being two sub-ways across each street, it is easy to see

that foot passengers may go in any direction desired on any side of either street without having to cross any stream of traffic whatever.

5 It will further be clear that foot passengers desiring to take the cars on street 2 may descend into sub-ways 61 or 63 and pass along the passages 83 to the isles of safety 84, and thus reach the cars without 10 having to cross any streams of traffic whatever at grade, and without incurring any risk of coming in conflict with any streams of traffic, all as will be clear from Figs. 1 and 5.

15 Another important feature of my invention resides in the fact that the spiral or helical ways 18, 20, 22 and 23 surround vacant spaces 85, 86, 87 and 88 respectively. These said spaces are sufficiently large to 20 afford the foundations for structures supporting high office buildings, so that the level passages 14, 15, 16 and 17 as well as the said helical or spiral passages may really be located underneath or on what would 25 be the first floor of modern office buildings, so that the cost of the real estate for this invention would be reduced to a minimum. The vacant spaces 90, 90', 91, 91', 92, 92', 93 and 93' inclosed between the said helical 30 and level passages and the said streets 1 and 2, can likewise be used for foundations of such buildings, or they in some instances may be employed for stores, or other purposes.

35 Coming now to the slightly modified form of the invention illustrated in Fig. 2, like numerals indicate the same parts as in Fig. 1, but the vacant spaces 90', 91', 92 and 93' are omitted, while the spaces lettered 85, 86, 40 87 and 88 in Fig. 1 are changed in shape and are here lettered 100, 101, 102 and 103. The doing away of the vacant spaces just mentioned, provides wider entrances to and from street 2 to the helical passages 18, 20, 45 22 and 23, as is respectively indicated by the numerals 104, 105, 106 and 107. It accordingly, is obvious from Fig. 2, that no stream of traffic need cross at grade any other stream of traffic, in order to go in any 50 possible direction which may be desired. It is further evident in connection with said Fig. 2, that no foot traveler need cross any street at grade or any stream of traffic at grade in going in any possible direction that 55 he may desire. The passages 83 and isle of safety 84 have been omitted in Fig. 2, since no street car tracks are there shown, but of course should street cars be placed upon street 2, the construction would be the same 60 in this particular as that illustrated in Fig. 1.

Coming now to the still further modified form of the invention illustrated in Fig. 3, the parts corresponding to those illustrated

in Figs. 1 and 2 have received the same reference numerals, but the vacant spaces 90, 91, 92' and 93 illustrated in Fig. 2 have been omitted, and the vacant spaces 85, 86, 87 and 88 appearing in Fig. 1 have been changed in shape. These said last named 65 spaces in Fig. 3, are respectively lettered 110, 111, 112, and 113. The level passages lettered 14, 15, 16 and 17 in Fig. 1 have been widened so as to accommodate traffic in both directions, and they are respectively designated 70 in Fig. 3 by the numerals 114, 115, 116 and 117. The passages 14 and 18 in Fig. 1 have been, in other words, consolidated into the single passage 114 in Fig. 3. Likewise the passages 15 and 20 in Fig. 1 75 have been consolidated into the passage 115 in Fig. 3, while the passages 16 and 22, and 17 and 23 in Fig. 1, have been respectively consolidated in Fig. 3, into the passages 116 and 117. This consolidation of passages not 80 only greatly widens the entrances into and out of street 2, but it also greatly widens the entrances into and out of street 1, all as will be clear from the drawings.

A further change in Fig. 3 over the preceding figure, resides in the fact that the car tracks lettered 120 and 121 have been placed on street 1, instead of street 2, and therefore the said car tracks traverse the bridge 3 instead of going under it. This 90 change in the car tracks necessitates the entrances and exits 123 and 124 pertaining to the sub-way 62 and of course similar entrances and exits can be provided in connection with the sub-way 60, should it be so desired. Isles of safety 125 and 126 are further illustrated in connection with the sub-way 62.

To summarize the broad invention included in all the figures, it will now be clear 105 that no stream of traffic need cross, at grade, any other stream of traffic in going in any one of the four directions it is possible for said stream to take. It will further be seen that whereas pedestrians may follow the 110 usual side walks or streets unmolested, yet should they wish to avoid crossing any stream of traffic whatever at grade, they can do so, by employing one or more of the sub-ways provided at this crossing. It will further be seen that when a vehicle has already 115 taken an up-grade, an up-grade will be followed when turning from one street into another, and will also be followed after having reached the desired street. It will further be observed that in the same way, when a stream of traffic in one street has taken a down grade, a down grade will be followed in taking a curved passage way to reach the other street, and to reach said other street, 120 a down grade will likewise be encountered, so that vehicles are not required to change the character of the grade when they are 125

leaving one stream of traffic and on entering another stream of traffic. This is an important feature of the invention.

It will further be seen that when the 5 curved passage ways for vehicles do not enter or leave a street on a tangent, they enter or leave the street on a very wide entrance or exit way so that vehicles will have ample room in which to turn from one 10 stream of traffic into another stream of traffic. It will further be observed that in practically every case where a congested state of traffic occurs, and where this crossing is therefore needed, that the real estate 15 necessary to provide this crossing will be of great value, and it is therefore a further important feature of this invention that vacant spaces such as 18 and 20, etc., are provided, practically at the very end of the via- 20 duct 3, so that pillars, columns, or other heavy supports can be accommodated on which tall office buildings may partially rest, and that therefore the upper stories of said buildings can over lie the curved passage 25 ways and thus the cost of the real estate will be reduced to a minimum.

It is obvious that those skilled in the art may vary the details of the invention without departing from the spirit thereof, and 30 therefore I do not wish to be limited to the above disclosure, except as may be required by the claims.

What I claim is:

1. In a street crossing the combination of 35 a viaduct on one street; a raised grade leading from the normal level of said street to said viaduct on each side of the latter; a depressed grade leading from the normal level of the other street toward said viaduct 40 on each side of the latter; and four ways for vehicles connecting said raised and depressed grades near the ends of said viaduct, substantially as described.

2. In a street crossing the combination of 45 a viaduct on one street; a raised grade leading from the normal level of said street to said viaduct on each side of the latter; a depressed grade leading from the normal level of the other street toward said viaduct on 50 each side of the latter; four ways for vehicles connecting said raised and depressed grades near the ends of said viaduct; and four ways connecting said normal levels of said streets outside of said first named four 55 ways, substantially as described.

3. In a street crossing the combination of a viaduct on one street; a raised grade leading from the normal level of said street to said viaduct on each side of the latter; a depressed grade leading from the normal level of the other street toward said viaduct on each side of the latter; and four curved inclined ways for vehicles connecting said raised and depressed grades near the

ends of said viaduct, substantially as de- 65 scribed.

4. In a street crossing the combination of a viaduct on one street; a raised grade leading from the normal level of said street to said viaduct on each side of the latter; a 70 depressed grade leading from the normal level of the other street toward said viaduct on each side of the latter, four curved inclined ways for vehicles connecting said raised and depressed grades near the ends 75 of said viaduct; and four level ways connecting said normal levels of said streets located outside of said first named four ways, substantially as described.

5. In a street crossing the combination of 80 a viaduct on one street; a raised grade between the normal level of said street to said viaduct on each side of the latter; a depressed grade extending from the normal level of said second street toward said via- 85 duct on each side of the latter; four ways connecting said raised and depressed grades on each side of said first named street leading from near the ends of said viaduct; four additional ways connecting the said normal 90 levels of said streets located outside of said first named four ways; and a subway under one of said streets near the ends of a pair of said additional ways, substantially as de- 95 scribed.

6. In a street crossing the combination of a viaduct on one street; a raised grade between the normal level of said street to said viaduct on each side of the latter; a depressed grade extending from the normal 100 level of said second street toward said via- duct on each side of the latter; four ways connecting said raised and depressed grades on each side of said first named street leading from near the ends of said viaduct; four 105 additional ways connecting the said normal levels of said streets located outside of said first named four ways; a subway under one of said streets near the ends of a pair of said additional ways; an isle of safety on 110 one of said streets; and a passage way from said subway to said isle of safety substantially as described.

7. In a street crossing the combination of a viaduct located on one street; raised 115 grades leading to said viaduct; and four passage ways for vehicles leading from said raised grades to the other street leaving four vacant spaces suitable for building supports near each end of said viaduct; substantially 120 as described.

8. In a street crossing the combination of a viaduct located on one street; raised grades leading to said viaduct; four curved passage ways for vehicles leading from said raised 125 grades to the other street leaving a plurality of vacant spaces suitable for building supports near said viaduct; and additional pas-

sage ways connecting said street; substantially as described.

9. In a street crossing the combination of a viaduct located on one street; raised grades leading to said viaduct; four passage ways for vehicles leading from said raised grades to the other street leaving four vacant spaces suitable for building supports near each end of said viaduct; and a plurality of subways

under said streets, near said crossing, for the 10 accommodation of pedestrians; substantially as described.

In testimony whereof I affix my signature, in presence of a witness.

ARTHUR HALE.

Witness:

T. A. WITHERSPOON.
